LANTERN

Harold Hoenisch, Albert Lea, Minn., assignor to King-
Seeley Thermos Co., a corporation of Michigan

Filed Dec. 19, 1960, Ser. No. 63,250

Term of patent 14 years

(Cl. D48—24)

I claim:

The ornamental design for a lantern, as shown.
